SURFACE ACTIVE AGENTS

Kendrick R. Eilar, Minneapolis, Minn., assignor
to General Mills, Inc., a corporation of Delaware

No Drawing. Application August 8, 1952,
Serial No. 303,433

6 Claims. (Cl. 260—513)

1

The present invention relates to surface active agents having the following formula:

in which R is a fatty group containing from 8-22 carbon atoms, R' is selected from the group consisting of hydrogen and $C(R'')_2SO_3M$, in which R'' is selected from the group consisting of hydrogen and lower alkyl groups, M is selected from the group consisting of alkali metal and ammonium, n is a small integer from 2 to 6 inclusive and m is a small integer from 1 to 6 inclusive, with the proviso that at least one of the groups R' is $C(R'')_2SO_3M$. These compounds are inexpensive surface active agents which may be used as wetting agents, foaming agents, detergents, emulsifiers and the like.

It is, therefore, an object of the present invention to provide novel compounds having the above formula.

It is another object of the present invention to provide a novel process of producing such compounds.

These compounds may be prepared by the reaction of a fatty polyamine having the formula $RNH(C_nH_{2n}NH)_nH$ in which the various symbols have the above significance, either with an alkali metal or ammonium sulfite or bisulfite and a carbonyl compound capable of forming a bisulfite addition product, or with such an addition product itself.

The fatty polyamines having the above formula may be made by various processes well known to those skilled in the art. The fatty polyamines which may be used include those derived from the mixed fatty acids of a fat or oil, from selected fractions of such fatty acids or any isolated fatty acid. The fatty polyamines may be either saturated or unsaturated. Typical fatty polyamines which may be employed are

The carbonyl compounds capable of forming bisulfite addition products include lower aldehydes and methyl ketones as well as other ketones such as cyclohexanone. Suitable carbonyl compounds include formaldehyde, acetaldehyde, acetone and the like. The preferred carbonyl compounds are those containing from 1-6 carbon atoms. The sulfite compound may be either an

alkali metal or ammonium sulfite or bisulfite. Typical examples include $NaHSO_3$, K_2SO_3 and NH_4HSO_3 . The sulfite or bisulfite compound and the carbonyl compound may be added to the reaction mixture as such, or they may be first combined to give the corresponding hydroxyalkane-sulfonate.

The number of alkanesulfonate groups introduced depends upon the relative proportions of the reactants. At least one alkanesulfonate group is introduced, and as many may be introduced as there are active hydrogens in the fatty polyamine. The method of preparation consists of heating the reactants together in a suitable solvent for from 1-4 hours at 60-100° C. The resulting solution may be used as such, or if it is desired to obtain the product as a dry solid, this may be done by adding to the collected reaction mixture a liquid in which the solvent is soluble but in which the product is insoluble. Suitable solvents include ethyleneglycol and suitable precipitants include acetone, methanol, ethanol, acetonitrile. In some instances, the fatty polyamine may be water-soluble, in which case water may be used as the reaction solvent.

Example 1

γ -Dodecylaminopropylamine,

(5.2 g.) was dissolved in 12 ml. of ethylene glycol. Sodium hydroxymethane - sulfonate monohydrate, $HOCH_2SO_3Na \cdot H_2O$ (9.1 g.) was added, and the mixture was heated on the steam bath for six hours. After cooling to room temperature the solution was poured into 200 ml. of acetonitrile. The precipitated white solid was removed by filtration, washed with fresh acetonitrile, and dried.

The product dissolved readily in water to give a solution of good surface active properties. A 0.25% solution gave 136 mm. of foam in the Ross-Miles test, a wetting time of 52.3 sec. in the canvas disc wetting test, and had a surface tension of 26.3 dynes per centimeter and an interfacial tension against mineral oil of 1.4 dynes per centimeter. The solution had a pH of 10.5 and was stable for several days without hydrolysis.

The product was composed principally of the following compound:

Example 2

γ -Tallowaminopropylamine (7.7 g.) was substituted for the γ -dodecylaminopropylamine in Example 1, and absolute methanol was substituted for acetonitrile. The product weighed 13 g. and gave a surface active aqueous solution; at a concentration of 0.25% it gave 110 mm. of foam in the Ross-Miles test and had a surface tension of 37.2 dynes/cm. and an interfacial tension of 21.6 dynes/cm.

The product was composed principally of the following:

where R represents the mixed fatty groups of tallow fatty acids.

Example 3

Example 1 was repeated substituting sodium 2-hydroxy-2-propanesulfonate (6.5 g.) for the hydroxymethanesulfonate and acetone for the acetonitrile. The product thus obtained was composed principally of the following compound:

This material gave aqueous solutions which foamed when shaken, although its solubility was limited to about 0.1%.

Example 4

To a solution of 20.8 g. of sodium bisulfite and 16.2 g. of 37% aqueous formaldehyde in 60 ml. of water was added 17.6 g. of N-dodecyl diethylenetriamine having the structure

The solution was heated on the steam bath until it became clear and homogeneous. It was then cooled and to it was added 400 ml. of absolute methanol with rapid stirring. After standing for 30 minutes, the white precipitate was removed by filtration and washed with methanol.

The product was highly surface active in aqueous solution; at a concentration of 0.25%, it gave 138 mm. of foam in the Ross-Miles test, a wetting time of 77.2 sec. in the canvas disc test. The surface tension of the solution was 32.6 dynes/cm., the interfacial tension 3.8 dynes/cm., and the pH was 9.8. The structure of this product is

Example 5

γ -Octadecylaminopropylamine was substituted for the dodecyl homolog of Example 1. The product was a strong surface tension de-

pressant, a 0.5% solution having a surface tension of 35.7 dynes/cm. and interfacial tension of 11.5 dynes/cm.

The product consisted chiefly of a compound 5 of the structure:

10 I claim as my invention:

1. Compounds having the following formula:

15 in which R is a fatty alkyl group containing from 8-22 carbon atoms, R' is selected from the group consisting of hydrogen and $\text{C}(\text{R}'')_2\text{SO}_3\text{M}$, in which R'' is selected from the group consisting of hydrogen and lower alkyl groups, M is selected from the group consisting of alkali metal and ammonium, n is from 2 to 6 and m is from 1 to 6, with the proviso that at least one of the groups R' is $\text{C}(\text{R}'')_2\text{SO}_3\text{M}$.

2. The following compound:

3. The following compound:

in which T represents the mixed fatty groups of tallow fatty acids.

4. The following compound:

5. The following compound:

6. The following compound:
